UNITED STATES PATENT OFFICE.

GEORGE D. DUDLEY, OF LOWELL, MASSACHUSETTS, ASSIGNOR TO WOODS,
SHERWOOD & LATHAM, OF SAME PLACE.

DESIGN FOR CARD-BASKETS.

Specification forming part of Design No. 5,917, dated June 11, 1872.

Specification describing a Design for a Basket for Cards, Photographs, &c., invented by GEORGE D. DUDLEY, of Lowell, in the county of Middlesex and State of Massachusetts.

The nature of my design is fully represented in the accompanying drawing, to which reference is made.

It is composed of the parts A B C, forming the body of the basket, and the legs D, and handle E. A is a strand of wire bent into a rectangular shape to form the rim, and having the wires B—which run from a central wire on the bottom of the basket horizontally a short distance and then up to the rim—bent over it and downward to form the loops C. E is the handle, connected with the ends and bottom of the basket by the braces F F, and serving both as a handle and a partition to separate the bas-

ket into compartments. The legs D are secured to the frame of the basket at each end, and are made of such form as to be in harmony with the general appearance of the other parts. The size of the basket may be varied so as to receive and hold cards, stereoscopic views, photographs, &c., of different sizes; and, if desired, it may be divided into several compartments by placing additional partitions in it.

Claim.

The design for a basket for cards, photographs, stereoscopic views, &c., substantially as shown and described.

GEORGE D. DUDLEY.
